Thomas Lewis.

UNITED STATES PATENT OFFICE.

THOMAS LEWIS, OF MALDEN, MASSACHUSETTS.

IMPROVEMENT IN BOTTLE-STOPPERS.

Specification forming part of Letters Patent No. 22,370, dated December 21, 1858.

To all whom it may concern:

Be it known that I, THOMAS LEWIS, of Malden, in the county of Middlesex and State of Massachusetts, have invented an Improved Tubular Self-Closing Bottle-Stopper; and I do hereby declare that the same is fully described and represented in the following specification and the accompanying drawings, of which—

Figure 1 is a top view of the said stopper; Fig. 2, a side elevation of it; Fig. 3, a vertical and longitudinal section of it; Fig. 4, a top view with the screw-cap removed. Fig. 5 is a bottom view of the said cap.

The bottle-stopper on which my improvement is made contains a ball-valve which is moved away from its seat when the stopper or bottle in which it may be is inclined or turned downward, the valve being returned upon its seat when the bottle or the stopper is in an upright position. Gravity effects the movement of the ball. Stoppers of this nature have been in use for many years. An improved stopper of the kind was patented by J. B. Williams, February 9, 1858. This stopper has the ball at the upper end of its discharging-tube, and kept in place by two arched wires or guides extending from the flange of the tube or seat of the ball, and around the ball. This disposition of the ball exposes it to the accumulation of dust, and as it is confined within the wire holders, which are permanently fixed to the discharging-tube, it is difficult to cleanse the ball.

In my improved stopper the ball and its seat are placed within a chamber furnished not only with a set of three or more guide-ribs, but with a separate screw-cap provided with retaining-bars or their equivalents, and a discharging mouth or tube. By unscrewing and removing the cap from the main tube, the ball can easily be taken out of the latter and cleansed. Furthermore, it is protected from dust, and by means of the guide-ribs of the chamber it is not only properly directed upon its seat, but is so held with reference to the column of fluid which may at any time be flowing through the stopper as to be lifted thereby, so as to cause the fluid to pass underneath the said ball and not spatter. I have found that when the current flows over the top of the ball, it generally spatters too much in passing from the tube. So, with respect to the stopper of the said Williams, another important disadvantage attending it is spattering of the liquid, the same being caused by the ball and its holding-wires. In my stop-

per I further prevent spattering by arranging in front of the retaining-bars of the screw-cap a tubular mouth for concentrating the stream after it may pass beyond the said bars.

In the drawings, A denotes the main body of the stopper as furnished with a broad flange or base, a, and a cork, b, applied below it and on a tube, c, which forms a conductor into the conical chamber d of the body A. At the lower part of said chamber is the valve-seat e, in which a ball-valve, B, rests. The inner surface of the chamber is furnished with three ribs, f f f, which project therefrom at equal distances apart, and keep the ball from touching the sides of the chamber while moving in the said chamber.

A separate screw-cap, C, furnished with cross-bars g h, and a tubular discharging-mouth, i, arranged as shown in the drawings, screws upon the upper end of the body A. This cap, however, may be fitted by a bayonet-catch instead of a screw. The cross-bars of the cap, when the stopper is inclined, detain the ball or prevent it from arresting the flowage of the fluid by the bars and into the discharging-mouth tube. At the same time, while the guide-ribs insure the passage of the fluid below the ball, so as to enable it to lift the ball and flow entirely underneath it, they act to prevent rotary motion of the fluid, and thus further operate to prevent spattering of it. Although the bars operate to prevent spattering of the fluid, they are of benefit in other respects, as they prevent the ball from sticking to the inner surface of the chamber and guide it to and from its seat. The discharging-mouth, by concentrating the stream flowing by the crossed bars, unites them again in one smooth stream.

I do not claim a tubular self-closing bottle-stopper having a ball-valve; nor do I claim the improved stopper as patented by the said Williams; but

What I do claim is—

My improved ball-valve stopper, as made with the separate cap C, provided with a discharging tubular mouth, i, and crossed bars g h, or equivalents, for detaining the ball, as described, and connected with the main tube or body by a screw or its equivalent.

In testimony whereof I have hereunto set my signature.

THOMAS LEWIS.
